United States Patent Office.

JOHN MORTON, OF WINCHESTER, INDIANA.

Letters Patent No. 72,527, dated December 24, 1867; antedated December 7, 1867.

IMPROVED RAILROAD-TRACK LIFTER.

The Schedule referred to in these Letters Patent and making part of the same.

TO ALL WHOM IT MAY CONCERN:

Be it known that I, JOHN MORTON, of Winchester, in the county of Randolph, and State of Indiana, have invented certain new and useful Improvements in the Machine for Raising and Adjusting the Tracks of Railroads, patented by myself; and I do hereby declare that the following is a full, clear, and exact description of the same, reference being had to the annexed drawings, making part of this specification, in which—

Figure 1 is an elevation, and

Figure 2 is a vertical cross-section.

The same letters are employed in the indication of identical parts in both figures.

My improvements relate to the mode of actuating the levers by which the hooks sustaining the track were suspended, as described in my Letters Patent for a machine for the before-recited purpose, dated March 19, A. D. 1867, to which patent I now refer for a description of the entire machine. In this specification I need not describe anything more than what may be necessary to enable persons skilled in the art to apply my improvements to a machine constructed in other respects according to the instructions and explanations therein contained.

In that machine provision was made for raising railroad-track by hooks suspended from the short arms of the crossed levers A, the fulcra of which were formed by the diagonal braces B. The crossed levers were, in the original machine, actuated by means of a system of levers which I wish to dispense with, substituting therefor the following-described arrangement of mechanism:

The levers A are depressed at their long arms by chains or cords C attached thereto, and extending downwardly, passing under the pulleys D, which are fastened by straps, or otherwise, to the braces B, and thence the chains are carried around the axle E', to which they are secured. This axle is placed in a slot in the vertical post L, and is turned by the spur-wheel F, of which it is part of the shaft. The outer bearing of the shaft E is formed in the cap F', fastened to the vertical post L. The spur-wheel F is driven by a pinion, G, placed on the axle of the winch H. L is a pawl, hooking into the cogs of the spur-wheel to hold the weight of the track after it has been raised by the levers A. The post L stands upon a pedestal, K, to which it is attached in such manner as to permit the post to oscillate upon the pedestal enough to accommodate itself to any inequalities of surface of the ground on which the latter rests. Hooks, as shown in my original patent, are suspended from the lower ends of the crossed levers A A at x x, which are to be attached under the rail, the base, K, standing on the track between the cross-ties. The track will then be raised by drawing down the upper ends of the levers A A.

What I claim as my invention, and desired to secure by Letters Patent, is—

1. The combination of the levers A, for raising railroad-tracks, with the chain or cord C, and the mechanism for actuating the same, substantially as set forth.
2. The arrangement of the mechanism for actuating the track-lifting levers A, said mechanism consisting of the parts C, D, E, F, G, and H, substantially as herein described.
3. The combination of the pedestal K, post L, braces B, and track-lifting levers A, arranged to operate substantially as and for the purpose set forth.

In testimony whereof, I have signed my name to this specification in the presence of two subscribing witnesses.

JOHN MORTON.
